FORMING DIE

Robert R. Harrison and Leslie H. Score, North Hollywood, Calif., assignors, by mesne assignments, to Bendix Aviation Corporation, South Bend, Ind., a corporation of Delaware

Application November 28, 1941, Serial No. 420,784

4 Claims. (Cl. 153—33)

This invention relates to forming dies and more particularly to a forming die for forming tube clamps from metal strip material.

Tube clamps are metal loops having holes at each end, designed to be placed around a tube and secured to a support by passing a screw or bolt through both holes in the ends of the loops. Large numbers of such clamps are used in the aircraft industry to secure hydraulic and electrical conduits to a frame member. The clamps are also useful in any application requiring a conduit of any type to be secured to a support.

It is an object of the invention to provide a forming die which will completely form a tube clamp from metal strip stock.

It is another object to provide a die which holds a strip of stock by punching a hole therein, holding the strip until a forming operation is completed, and having means to then cut off the strip to release it from the punching mechanism.

Still another object is to provide a die which forms strip material into loops by forcing a mandrel between two supports upon which a strip of stock rests.

Another object is to provide a die which completes the forming of a strip about a mandrel by having a pivoted cross-arm member strike a protruding end of the strip and bending it over upon the mandrel.

A further object is to provide a die wherein tube clamps are formed on a mandrel and take-off means are provided which force the tube clamps off of an open end of the mandrel.

In the drawings forming a part of this specification:

Figure 1 is a side view in elevation and partly in section of a die made in accordance with the invention showing the die in an open position to permit insertion of metal strip stock therein;

Figure 2 is a side view in elevation and partly in section of the die showing the die in the lowermost portion of its forming stroke;

Figure 3 is a top view in section of the lower bed of the die, the section being taken along the line 3—3 of Figure 1;

Figure 4 is a sectional view of the die along the line 4—4 of Figure 3; and

Figure 5 is an isometric view of a tube clamp made by the die of this invention.

Referring to Figure 1, the die comprises a bottom bed plate 10 having upright guide posts 12 secured thereto. Guided on post 12 is an upper bed plate 14 which is free to reciprocate with relation to the bottom bed plate 10. Secured to bed plate 10 is a punch block 16 on one side,

and spaced therefrom on the left is a pivot block 18.

Pivoted to block 18 is a shaft 20 having a gear 22 secured thereto, and having an arm 24 also secured thereto. At the outer end of arm 24 is secured a rod 26 which is axially parallel to the shaft 20. Also pivotally secured to block 18 is a toothed quadrant 28 pivoted at 30 engaging the teeth of gear 22. When quadrant 28 rotates about its axis it causes gear 22 to rotate also which in turn causes the arm 24 to pivot on the shaft 20. One end of quadrant 28 is secured to a member 32 having a lost motion connection with a socket member 34, the movement being limited by a pin 36 in member 32 sliding in a slot 38 in socket member 34. Socket member 34 is in turn pivotally connected to the upper bed plate 14.

Secured to the upper bed plate 14 with a lost motion connection is a mandrel support 40 having rigidly secured thereto a mandrel 44. When the upper bed plate 14 moves downwardly towards bed plate 10 the mandrel support 40 moves with it, forcing the mandrel 44 in opening 17 between the blocks 16 and 18.

Rigidly secured to upper bed plate 14 is a block 50 on which are mounted a punch member 52, a punch member 54, and a cutter 56. Punch 52 is guided at its lower end by block 58 yieldingly secured to block 50 by pin 60 and compression spring 62. Punch 54 is similarly guided by block 64 secured to block 50 by pin 66 and spring 68.

The punch block 16 contains punch holes for the punches 52 and 54 and the cutter 56. Punch hole 70 receives the punch 52, punch hole 72 receives punch 54, and punch hole 74 receives cutter 56.

A tube clamp which is formed by the die of this invention is shown in Figure 5. The clamp comprises a strip of metal 80 formed into a loop, with one end of the strip tangent to the loop, and with the other end of the loop bent at right angles to the loop shape to be parallel with the first end. A hole 82 is formed at each end of the loop 80, and both are axially aligned in the finished loop.

The clamps 80 are made from long strips of material which may be of any suitable metal such as aluminum. Referring to Figure 1, a strip 84 is inserted in the die, and rests on punch block 16 and pivot block 18. The extent to which the strip 84 is inserted in the die may be limited by automatic feeding mechanisms (not shown) which are available on the market, or may be limited by a stop 86 secured to the pivot block 18.

After the strip 84 is inserted in the die as shown in Figure 1, the upper bed plate 14 is forced

downwardly toward the lower plate 10, the guide blocks 58 and 64 striking the strip 84 first. These guide blocks hold the strip tightly, and further movement of the upper plate 14 causes punch 54 to pierce the strip 84 and pass therethrough into punch hole 72. Shortly thereafter during further movement, the punch 52 also pierces the strip 84 forming a second hole therein.

Immediately after the punch 54 has passed through strip 84 and into its hole 72 the mandrel 44 descends upon the strip 84 and pulls the strip downwardly between the two blocks 16 and 18. Since the right end of the strip is held by punch 54, the left end is the free end and consequently must slide into the hole 17 between the two blocks as the mandrel pulls it downwardly. At the lower limit of the movement of the mandrel 44, the strip 84 will be formed as shown in Figure 2, with the free or left end sticking upwardly as shown in dotted lines in Figure 2.

During the stroke of the die when plate 14 is moving toward plate 10, the quadrant member 28 is also actuated. Member 32 slides upwardly into its socket member 34 until the two abut. Thereafter these two members cause the quadrant 28 to be rotated about its pivot 30, and this in turn rotates gear 22. The consequent rotation of shaft 20 causes arm 24 to rotate also, until the resultant position at the end of the stroke of the die is that shown in Figure 2. While passing to the extreme position shown in Figure 2, the arm 24 and its rod 26 engage the upper right end of strip 84 (as shown in dotted lines in Figure 2) and forces it down upon the mandrel 44. This action completes the tube clamp as shown in Figure 2.

Near the end of the stroke of plate 14 toward plate 10, and after the tube clamp is substantially completed the cutter 56 reaches the strip 84 and passes therethrough into its punch hole 74, cutting the left end of the strip completely off from the main body of the strip 84. This action, however, occurs only after the mandrel 44 has securely gripped the strip against the punch block 16, and this succession of operations is made possible by the lost motion connection of mandrel support 40 to the upper bed plate 14.

After the plates 14 and 10 have reached the position shown in Figure 2 they are thereafter separated by any suitable mechanism, and this return stroke causes quadrant 28 to rotate to its original position as shown in Figure 1 rotating the arm 24 counter-clockwise and causing the rod 26 to rest in the hole 27 in the pivot block 18. The cutter 56 is also withdrawn. The guide blocks 64 and 58 remain pressed against the strip 84 by their springs 68 and 62 respectively, until the punches 54 and 52 are withdrawn out of the holes formed in strip 84. In the final opened position, the parts have the relative positions shown in Figure 1 except that finished tube clamps are secured around the mandrel 44. The finished tube clamps are removed from the mandrel 44 by a push-off device 46 which will be more completely described later.

The pivot block 18 is adjustably movable on the bottom bed plate 10. By moving the block 18 to the right or left (Figures 1 and 2) the opening 17 may be made larger or smaller. This variable opening 17 thus accommodates larger or smaller size clips 80 when the mandrel 44 is made correspondingly larger or smaller. For example one die made in accordance with the invention can make clips varying from three quarters of an inch in diameter to two and a half inches in diameter.

The forming die is preferably a multiple die as shown in Figure 3. There it will be seen that there are four strips 84 inserted into the die at one time. The punches 52 and 54 are also four in number as well as the cutter 56. The mandrel 44 is made long enough to act on all four strips 84, and the pivoted rod 26 is made of similar proportions.

The details of the mandrel and its push-off mechanism are shown in Figure 4. The support member 40 is L shaped with the mandrel 44 rigidly secured to the vertical arm of the L. Since the mandrel 44 would not be rigid when acting as a cantilever arm, a pivoted support member 42 is provided on the left end of mandrel support 40, and engages the upper surface of mandrel 44. A leaf spring 43 urges the pivoted support member 42 to a vertical position. The push-off mechanism comprises a crescent shape member 46 shown most clearly in Figure 1. Crescent shape member 46 is secured to a rod 48 having a head 47, the assembly being urged toward the right by a compression spring 49 resting upon one leg of the mandrel support 40.

When it is desired to remove the finished tube clamps from the mandrel 44 the rod 48 is moved inwardly by manual or power means, and the crescent shape member 46 moves along the lower half of the mandrel 44 shoving finished clamps off of the left end of the mandrel 44. When the clamps strike pivoted support member 42 when moving to the left, this member freely rotates clockwise to provide a clearance, since there is no load on the mandrel at the same time.

In operation, strip metal 84 is moved into the open die as shown in Figure 1. As the die is closed the guide blocks 64 and 68 touch the strip 84 first, and punches 54 and 52 pass through the strip, anchoring it as well as punching it. At the same time the mandrel 44 descends on the strip pulling the left end thereof into the opening 17 between blocks 16 and 18, causing the free end of the strip to assume an upright position as shown by the dotted lines in Figure 2. Simultaneously the quadrant 28 is rotated by its actuating mechanism causing the arm 24 to rotate allowing rod 26 to strike the upright end of the strip 84 and bend it flat upon the mandrel 44 as shown in Figure 2. Near the end of the closing stroke of the die, the cutter 56 cuts off the left end of the strip, severing the completed tube clamp (Figure 5) from the body of the strip 84.

The arrangement of parts in the die is such that the hole punched by the punch 52 forms the hole on the right end or bottom end of the next finished tube clamp as it is completed on the mandrel 44. The hole punched by the punch 54 is the hole for the left end or upper end of the next succeeding finished tube clamp.

When the die is opened the finished tube clamps will be pressed around the mandrel 44. The push-off mechanism (shown most clearly in Figure 4) is then operated either manually or by power mechanism. The rod 48 is moved to the left moving the crescent shaped member 46 along the mandrel 44, pushing the finished clamps off of the left end of the mandrel. During this operation the pivoted support leg 42 pivots clockwise to provide clearance for the finished tube clamps.

Although this invention has been described with reference to a particular embodiment thereof it is not limited to this embodiment nor otherwise except by terms of the following claims.

We claim:

1. A tube clamp die for forming a strip of metal into a loop having generally tangential ends, comprising two spaced supports upon which the metal strip rests when in the flat form, movable means adapted to close on said strip to lock it to one of said supports, the portion of the strip on the other support being free, a movable mandrel adapted to move between said supports and contact said strip to form it in a generally semicircular form, the secured end being formed radially to said semicircular portion, and pivoted means to strike the unsecured end of said strip and bend it about the mandrel until the end is in a position generally parallel to the secured end, to form the completed metal article, the die being characterized in that said two spaced supports define a recess therebetween of greater depth than said mandrel when the latter is moved between said supports, whereby the strip is unsupported between said two supports and is shaped against said mandrel solely by tension.

2. A tube clamp die for forming a strip of metal into a loop having generally tangential ends, comprising upper and lower bed plates relatively movable toward each other, two separated blocks secured to one of said plates against which the metal strip is adapted to rest, a locking block upon the other plate, adapted to contact the strip on one block to lock it thereto, the other end of the metal strip being free, a mandrel of generally round cross section secured to said other plate and adapted to be moved between said blocks to form the strip in a semicircular shape, the secured end being bent generally radially to the semicircular shape, and arm means pivoted to one of said bed plates and adapted to strike the free end of said strip and bend it about the mandrel until that end is generally parallel to the locked end, said die being characterized in that said two spaced supports define a recess therebetween of greater depth than said mandrel when the latter is moved between said

supports, whereby the strip is unsupported between said two supports and is shaped against said mandrel solely by tension.

3. A tube clamp die for forming a strip of metal into a loop having generally tangential ends, comprising two spaced supports upon which the metal strip rests when in flat form, movable means adapted to close on said strip to lock it to one of said supports, the portion of the strip on the other support being free, a mandrel adapted to move between said supports and contact said strip to form it in a generally semicircular shape, the secured end being formed radially to said semicircle, pivoted means to strike the unsecured end of said strip to bend it about the mandrel until the end is in a position generally parallel to the secured end, to form the completed metal tube clamp, said mandrel being a cantilever structure, a pivoted leg normally supporting the free end of the cantilever, and means adapted to move along said mandrel to push off of the same the completed tube clamps, said pivoted leg being pushed aside during this step.

4. A forming mechanism for bending a strip into a substantially closed curve comprising: a mandrel and cyclically operable means cooperating therewith for wrapping a work strip about said mandrel, said means exerting lateral force against said mandrel during only a portion of each cycle; supporting means for said mandrel for resisting lateral force including a rigid support connected to said mandrel at one end thereof, and a pivoted leg normally supporting the other end of said mandrel against said lateral force; and means adapted to move along said mandrel to push off of it strips that have been bent there around, during a portion of said cycle when said means is not exerting lateral force on said mandrel, said pivoted leg being pushed aside by the bent strips to permit their discharge off the end of the mandrel.

ROBERT R. HARRISON.
